DOOR CHECK

Henry M. Borden, Minneapolis, Minn.

Application October 20, 1941, Serial No. 415,751

13 Claims.

(Cl. 16—85)

My present invention relates to door checks intended for general use in checking the closing movement of spring-closed doors, and, more particularly, screen doors.

The objects of the invention are: first, to progressively decrease the speed and force of the closing of a spring-actuated door; second, to provide a door check that is held inoperative by a spring-actuated door when closed; and third, to provide a door check that is automatically set into an operative position as the door is opened.

Other objects of the invention will be apparent from the following description, reference being had to the accompanying drawing.

To the above end, generally stated, the invention consists of the novel construction and arrangement of parts hereinafter described and defined in the claims.

In the accompanying drawing, which illustrates the invention, like characters indicate like parts throughout the several views.

Referring to the drawing:

Fig. 1 is a top plan view of the improved door check in an operative position in a door frame, fragmentarily shown in horizontal section, having a spring-closed screen door hinged thereto;

Fig. 2 is a front elevation of the improved door check, full size, attached to the head jamb of the door with its buffer and impeller positioned as held when the door is closed;

Fig. 3 is a top plan view of the door check, as shown in Fig. 2, with some parts shown in different positions by means of broken lines;

Fig. 4 is a view partly in side elevation and partly in section taken on the line 4—4 of Fig. 3;

Fig. 5 is a view corresponding to Fig. 4 but showing the impeller held in an operative position by the buffer; and

Fig. 6 is a fragmentary detail view of the roller-equipped end of the buffer.

The numeral 7 indicates a door frame having a rabbeted seat 8 in which a screen door 9 is hinged at 10 to said frame and yieldingly held closed by a coiled spring 11 anchored to said frame and attached at 12 to the door 9.

My improved door check is a self-contained unit and includes a bracket 13, a buffer 14, and an impeller 15. The bracket 13, as shown, is a flat plate having its end portions first bent laterally upwardly into parallel arrangement to afford side members 16 that space said bracket from the door frame 7, and then bent outwardly to afford outturned feet 17 which bear against the under side of the head jamb of the frame 7 and secured thereto by screws 18. In applying the bracket 13 to the door frame 7, it is positioned thereon the proper distance, as per instructions, from the hinged edge of the door 9 with its outer longitudinal edge flush with the inner face of the rabbet 8.

The buffer 14 is a Z-shaped lever having an intermediate section 19, a short inner arm 20 on the inner end of said section and a long outer arm 21 on the outer end of said section. This buffer 14 is pivoted to the bracket 13 at the elbow, between the intermediate section 19 and the short arm 20, as indicated at 22. The arms 20 and 21 extend in opposite directions from the intermediate section 19 and substantially at right angles thereto. The long arm 21 has an adjustable outer section 23 having on its outer end a bifurcated bearing 24, between the prongs of which a rubber door-engaging roller 25 is journaled. Said long arm 21 has a channel 26 in its outer end portion in which the arm section 23 is mounted for endwise sliding adjustment to vary the operative length of the buffer 14. A screw 27 having threaded engagement with the long arm 21 extends through a long slot 28 in the arm section 23 and rigidly but adjustably secures said section to the arm 21. A coiled spring 29 is anchored at one end to the bracket 13, as indicated at 30 and attached at its other end of a depending lug 31 on the free end of the short arm 20. The spring 29 is under strain to swing the buffer 14 into a position, indicated by broken lines in Fig. 3, when the door 9 is open and in which position the roller 25 is in the path of the closing movement of said door. When the door 9 is closed, the tension of the spring 29 is sufficient to overcome the tension of the spring 29 and hold the buffer 14 positioned, as indicated by full lines in Fig. 3.

The impeller 15 is in the form of a lever comprising an inner section 32 and an outer section 33, said former section being pivoted relatively close to its inner end to the bracket 13, as indicated at 34 for horizontal swinging movement. In the pivoted end portion of the impeller section 32 is a channel 35 into which the inner end portion of the impeller section 33 extends and is pivoted at 36 to the side members of the channel 35 for vertical swinging movement. When the impeller section 33 is in a horizontal position, the side members of the channel 35 rigidly hold said section for common horizontal swinging movement with the impeller section 32. The end portion of the impeller section 33 is bent laterally away from the roller-equipped end of the buffer 14. On the outer end of the impeller section 33 is a bifurcated bearing 37 between the prongs of which a door-engaging rubber roller 38 is pivoted. A coiled spring 39 is anchored at one end of the bearing 37, as indicated at 40, and attached at its other end to a depending lug 41 on the outer end of the impeller section 32. When the spring 39 is inactive, it normally holds the impeller section 32 positioned, as indicated by full lines in Fig. 3. Normally the impeller sec-

tion 33 is gravity held in a depending position. See Figs. 2 and 4.

A depending cam 42, on the pivoted end portion of the impeller section 33, is arranged to be engaged by the intermediate section 19 of the buffer 14 and lifts the impeller section 33 into an operative position as said buffer is released by the opening of the door 9 and swings outwardly into an operative position. See Figs. 4 and 5. The intermediate section 19 of the buffer 14 is downwardly offset at 43 for free horizontal swinging movement under the impeller section 32 and spring 29. See Figs. 2 and 4.

The operation of the improved door check may be briefly described as follows: The door 9 being yieldingly held closed by the coiled spring 11 holds the buffer 14 retracted, against the tension of its actuating spring 29, as indicated by full lines in Figs. 2 and 3, and the impeller section 33 is gravity held in a depending inoperative position. See Figs. 2, 3 and 4. When the door 9 is opened, pressure thereof on the roller 25 is removed and the spring 29 swings the buffer 14 into an operative position, as indicated by broken lines in Fig. 3, and in which position it projects horizontally into the path of the closing movement of said door. The path of movement of the door-engaging roller 25, as the buffer 14 swings to or from operative positions, is indicated by the letter A. During the final projecting movement of the buffer 14, as the door 9 is being opened, the cam 42 is engaged by the intermediate section 19 of said buffer and lifted into a horizontal position with its door-engaging roller 38 in the path of the closing movement of said door, as shown by broken lines in Fig. 3 and by full lines in Fig. 5. The path of movement of the door-engaging roller 38 is indicated by the letter B, as the impeller section 33 is lifted by the buffer 14 acting on the cam 42, from a gravity-held inoperative position to an operative position. The impeller section 33 is returned to an inoperative position by the action of gravity. The inner face of the door, when closed, is indicated by the broken line C. See Fig. 3.

When the door 9 is released, upon the completion of its opening movement, its spring 11 swings said door toward a closed position. As the door 9 approaches its closed position, it first engages the roller 25 and swings the buffer 14 toward an inoperative position, against the tension of the spring 29. As the buffer 14 moves with the door 9, it releases the cam 42, but before the impeller arm 33 has time to drop under the action of gravity, its roller 38 is engaged by the door 9 and thereby frictionally held and retains said arm in an operative position. The force of the closing movement of the door 9 will also swing the impeller 15 away from the buffer 14 and toward the door frame 7. This swinging movement of the impeller 15 places the spring 39 under tension and when the tension thereof is increased sufficiently to overcome the force of the closing movement of the door 9 and stop the same, the tensioned springs 29 and 39, respectively, will impart partial opening movement to the door 9. When the spring 11 overcomes the force of the return opening movement of the door 9, it will again swing said door toward a closed position. During the second closing movement of the door 9, it will again engage the rollers 25 and 38, but with a diminished force and again operate the buffer 14 and the impeller 15 and place the springs 29 and 39, respectively, under tension. The tensioned springs 29 and 39 will again im-

part another but slower return opening movement to the door 9 and of not such a wide extent as the first return opening movement thereof. When the tensioned spring 11 has overcome the force 5 of the second return opening of the door 9, it will swing said door to a closed position and at which time the door 9 will engage the roller 25 but before it has time to engage the roller 38 due to its slowed closing movement of the door 9, the impeller arm 33 will drop by gravity and the pressure of the door 9 on the roller 25 will move the buffer 14 into an inoperative position and allow the door 9 to completely close.

In case pressure is applied to the door 9 in closing the same, the springs 29 and 39 will yield and permit the buffer 14 and the impeller 15 to move with the door 9 into inoperative position without placing undue strain on the door check.

From the above description, it is evident that 20 my improved door check will progressively decrease the speed and the force of the closing of the door 9 and allow the same to close quietly.

From what has been said, it will be understood 25 that the door check described is capable of modifications as to details of construction and arrangement within the scope of the invention herein disclosed and claimed.

What I claim is:

1. In a door check, a bracket applicable to a 30 door frame having a yieldingly closed door hinged thereto, a spring-actuated buffer mounted on the bracket and normally yieldingly held in an inoperative position by the door when closed, said buffer being constructed and arranged to move into the path of the closing movement of the door when the door is opened and interrupt the closing movement of the door, an impeller mounted on the bracket for imparting return opening movement to the door at the time the closing movement thereof is interrupted by the buffer, said impeller being normally yieldingly held in an inoperative position, when the door is closed, and means actuated by the buffer during its movement to an operative position to move said impeller into an operative position.

2. In a door check, a bracket applicable to a 50 door frame having a yieldingly closed door hinged thereto, a spring-actuated buffer mounted on the bracket and normally yieldingly held in an inoperative position by the door when closed, said buffer being constructed and arranged to move into the path of the closing movement of the door when the door is opened and interrupt the closing movement of the door, an impeller mounted on the bracket for imparting return opening movement to the door at the time the closing movement thereof is interrupted by the buffer, said impeller being normally gravity held in an inoperative position when the door is closed, and a cam on the impeller constructed and arranged to be engaged by the buffer during its movement to an operative position and move said impeller into an operative position.

3. In a door check, a bracket applicable to a 60 door frame having a yieldingly closed door hinged thereto, a buffer for interrupting the closing movement of the door, said buffer being in the form of a bell-crank fulcrumed to the bracket and having a long arm and a short arm and a spring connecting the short arm to the bracket and under strain to move the buffer and project its long arm into the path of the closing movement of the door, when open, said buffer being normally held in an inoperative position by the 70 door when closed, an impeller mounted on the

bracket for automatically imparting return opening movement to the door at the time the closing movement thereof is interrupted by the buffer, said impeller being normally yieldingly held in an inoperative position when the door is closed, and means actuated by the buffer during its movement into an operative position to move the impeller into an operative position.

4. In a door check, a bracket applicable to a door frame having a yieldingly closed door hinged thereto, a buffer mounted on the bracket for automatically interrupting the closing movement of the door, and an impeller mounted on the bracket for imparting return opening movement to the door at the time the closing movement thereof is interrupted by the buffer, said impeller being in the form of a lever comprising an inner arm and an outer arm, said inner arm being fulcrumed to the bracket at its inner end portion for horizontal swinging movement, a spring connecting the inner arm at its outer end to the bracket, and a joint connecting the outer arm at its inner end to the inner end of the inner arm for common horizontal swinging movement therewith but with freedom for independent vertical swinging movement, said outer arm when the door is closed being in a vertical inoperative position, and means actuated by the buffer during its movement to an operative position for moving said outer arm from a vertical or inoperative position into a horizontal or operative position in which it extends into the path of the closing movement of the door when open.

5. The structure defined in claim 4 in which the means actuated by the buffer is a cam on the outer arm of the impeller constructed and arranged to be engaged by the buffer.

6. The structure defined in claim 4 in which the outer arm of the impeller, when in an inoperative position, is gravity held in a depending position.

7. In a door check, a bracket applicable to a door frame having a yieldingly closed door hinged thereto, a buffer mounted on the bracket for automatically interrupting the closing movement of the door, and an impeller mounted on the bracket for imparting return opening movement to the door at the time the closing movement thereof is interrupted by the buffer, said impeller being in the form of a lever comprising an inner arm and an outer arm, said inner arm being fulcrumed to the bracket at its inner end portion for horizontal swinging movement, a spring connecting the inner arm at its outer end to the bracket, and a joint connecting the outer arm at its inner end to the inner end of the inner arm for common horizontal swinging movement therewith but with freedom for independent vertical swinging movement from a horizontal position to a depending position in which it is gravity held, said joint limiting the vertical swinging movement of the outer arm and aligning the same with the inner arm, said outer arm when the door is closed being in a depending position, and means on the outer arm constructed and arranged to be engaged by the buffer during its movement to an operative position for lifting the outer arm into a horizontal position in which it extends in the path of the closing movement of the door when open.

8. The structure defined in claim 7 in which the outer arm when engaged by the door being held thereby is in a horizontal position and released from the door during opening movement thereof

for return by gravity to an inoperative position.

9. In a door check, a bracket applicable to a door frame having a yieldingly closed door hinged thereto, a buffer mounted on the bracket for automatically interrupting the closing movement of the door, and an impeller mounted on the bracket for imparting return opening movement to the door at the time the closing movement thereof is interrupted by the buffer, said impeller being in the form of a lever comprising an inner arm and an outer arm, said inner arm being fulcrumed to the bracket at its inner end portion for horizontal swinging movement, a spring connecting the inner arm at its outer end to the bracket, and a joint connecting the outer arm at its inner end to the inner end of the inner arm for common horizontal swinging movement therewith but with freedom for independent vertical swinging movement, said outer arm when the door is closed being in a vertical inoperative position, and a cam on the outer arm of the impeller, said buffer having a section extending transversely under the impeller and arranged to engage said cam during movement of the buffer to an operative position and move the outer arm of the impeller into an operative position.

10. A check for a yieldingly closed door comprising a buffer for interrupting the closing movement of the door, said buffer being yieldingly held in an inoperative position by the door when closed, and an impeller for imparting return opening movement to the door when closing movement thereof is interrupted by the buffer, said impeller being yieldingly held in an inoperative position when the door is closed, said buffer being constructed and arranged to move the impeller into an operative position, during movement of the buffer to an operative position when released by the opening of the door, and temporarily holding the same, said impeller having an actuating spring arranged to be placed under tension by the door during closing thereof.

11. The structure defined in claim 10 in which the door, during its closing movement temporarily holds the impeller in an operative position and releases the buffer therefrom.

12. A check for a yieldingly closed door comprising a buffer for successively interrupting the closing movement of the door with progressively diminishing force, said buffer being yieldingly held in an inoperative position by the door when closed, and an impeller for imparting return opening movements to the door with progressively decreasing force each time closing movement thereof is interrupted by the buffer, said impeller being yieldingly held in an inoperative position when the door is closed, said buffer being constructed and arranged to move the impeller into an operative position, during movement of the buffer to an operative position when released by the opening of the door, and temporarily holding the same, said impeller having an actuating spring arranged to be placed under tension by the door during closing thereof.

13. The structure defined in claim 12 in which the door during its interrupted closing movements first engages the buffer and thereafter engages the impeller and frictionally holds the same in an operative position before the closing movement of the door moves the buffer sufficiently to release the impeller.
